(57) **CLAIM**

The ornamental design for a universal tablet hand strap holder device, as shown and described.

DESCRIPTION

FIG. 1 is a front perspective view of a universal tablet hand strap holder device, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear view showing a first alternate state with additional environment;

FIG. 9 is a rear view showing a second alternate state with additional environment; and,

FIG. 10 is a rear perspective view showing a third alternate state.

The broken lines in FIGS. 8 and 9 illustrate environment and form no part of the claimed design.

1 Claim, 10 Drawing Sheets
